UNITED STATES PATENT OFFICE.

ALFRED MILLEMAN, OF SWISSVALE, PENNSYLVANIA.

ATTACHMENT FOR COMBINATION SQUARES.

Application filed December 14, 1925. Serial No. 75,212.

My invention relates to an attachment for combination squares, and the primary object thereof is to provide an attachment which is designed to be connected to a combination square and adapted for use as a surface gauge, height gauge, for scribing lines, leveling plane work, or for any other uses wherein it is found to be applicable, under such conditions providing an inexpensive efficient instrument serving as a substitute for costly instruments of the kind for the uses set forth.

Further objects of the invention are to provide a device of the type stated, which is simple in its construction and arrangement, strong, durable and efficient in its use, accurate, readily adjustable and comparatively inexpensive to manufacture.

With the foregoing and other objects 20 in view, which will appear as the description proceeds, the invention resides in the combination and arrangement of parts and in the details of construction hereinafter described and claimed, it being understood that 25 changes in the precise embodiment of the invention hereinafter disclosed can be made within the scope of what is claimed without departing from the spirit of the invention.

In the drawing wherein like numerals of 30 reference designate corresponding parts throughout the several views:—

Figure 1 is a side elevational view of a combination square provided with an attachment in accordance with my invention.

Figure 2 is an enlarged vertical sectional view of the slide with associated parts.

Figure 3 is an enlarged transverse sectional view of the slide on line III—III, Figure 1.

Figure 4 is an enlarged horizontal view of the supporting screw.

Figure 5 is an enlarged plan view of the clamping collar.

Figures 6 and 7 are respectively side and 45 end views of the slide liner member.

Referring in detail to the drawing 1 denotes a leveling base secured to the lower end of a scale blade 2. The base 1 and blade 2 constitutes a combination square commonly used by mechanics for purposes well known in the art to which my invention appertains.

A rectangularly shaped slide 3, provided with a vertically disposed slot 4, is shiftably mounted on the blade 2. The latter extends through the slot 4. The slide 3 consists of two half sections respectively indi-

cated at 5 and 6, which are permanently secured together by a plurality of rivets 7, during the assembly of the slide.

The slide section 5 is provided with a centrally disposed aperture 8 having a countersunk inner end 9. A supporting screw 10 is rotatably mounted in the aperture 8, and projects laterally from the slide section 5. The screw 10 has a tapered head 11 which 60 seats in the counter sunk inner end 9 of the aperture 8 and is flush with the inner face of the slide section 5. The screw 10 is positioned in the aperture 8 before the slide sections 5 and 6 are assembled in the manner above stated.

The supporting screw 10 is provided with a transversely extending aperture 12 which is disposed adjacent to the inner end thereof. A scribe or needle 13 is mounted in the 75 aperture 12 and is frictionally slidable therein. Clamping collars 14 and 15 are mounted on the supporting screw 10 and are positioned on respective sides of the needle 13. The collars 14 and 15 are provided on their 80 opposed faces with transversely extending rounded grooves 16 for augmenting their engagement with the needle 13. The collar 15 is closely fitted intermediate of the outer face of the slide section 5 and of the needle 13, and the collar 14 is disposed on the outer side of the needle 13 and is engaged by a knurled locking nut 17. The nut 17 threadably engages the supporting screw 10 and its adjustment thereon simultaneously secures the supporting screw 10 against rotation in the slide 3, and the needle 13 against longitudinal movement in the supporting screw aperture 12, whereby the needle may be readily locked in the required position. 95

The slide section 6 is provided with a centrally disposed threaded aperture 18 in which a locking bolt 19 is threadably engaged. The bolt 19 is formed with a knurled head 20 to facilitate its manipulation. 100

A flat liner member 21 is disposed in the slide slot 4 and is disposed intermediate of the inner side of the slide section 6 and of the scale blade 2. The ends 22 of the liner member 21 are disposed at right angles and overlaps the respective end edges of the slide section 6 for preventing the longitudinal movement of the liner member 21 in the slide slot 4.

The inner end of the locking bolt 19 engages the liner member 21 when the former is set for locking the slide 3 against move-

ment of the scale blade 2. The provision of the liner member 21 eliminates the objectionable feature of a direct engagement of the locking bolt 19 with the scale blade 2, 5 as such engagement would tend to deface or mar the surface of the scale blade 2.

One end 23 of the needle 13 is formed with a straight point intended for scribing lines and the other end 24 thereof is also 10 pointed and disposed at right angles to adapt it for use as a height and surface gauge in the usual manner.

The use of my attachment in connection with a combination square will provide an 15 accurate readily adjustable device of the kind set forth and serve as an adequate, inexpensive substitute for surface gauges as now ordinarily constructed.

What I claim is:

20 The combination with a combination square including a blade, of an attachment comprising a rectangularly shaped slide provided with a slot for the passage of said blade one side wall of said slide formed 25 with an interiorly counter sunk aperture and the other side wall thereof formed with

a threaded aperture, a supporting screw provided with a tapering head, rotatably mounted in said counter sunk aperture, said supporting screw formed with a transverse 30 aperture, a needle element extending in said transverse aperture and longitudinally shiftable therein, a pair of grooved clamping collars mounted on said supporting screw and disposed on respective sides of 35 said needle element, a nut threadably mounted on said supporting screw and engaging one of said pair of collars for locking said supporting screw against rotation in said counter sunk aperture and for locking said needle element against longitudinal movement in said transverse aperture, a liner member mounted in said slot, the end portions of said liner member overlapping the 40 respective end edges of one of said side 45 walls, a locking bolt threadably mounted in said threaded aperture, and engaging said liner member for locking said slide against movement on said blade, substantially as described and for the purpose set forth. 50

In testimony whereof I affix my signature.

ALFRED MILLEMAN.
